UNITED STATES PATENT OFFICE.

ELDON R. WATKINS, OF KINGMAN, KANSAS.

AUTOMATIC WHISTLE-ACTUATING MECHANISM FOR LOCOMOTIVES.

Application filed July 11, 1923. Serial No. 650,752.

To all whom it may concern:

Be it known that I, ELDON R. WATKINS, a native-born citizen of the United States, residing at Kingman, in the county of Reno 5 and State of Kansas, have invented certain new and useful Improvements in Automatic Whistle-Actuating Mechanism for Locomotives, of which the following is a specification.

10 In carrying out the present invention, it is my purpose to provide a whistle actuating mechanism for locomotives that is automatic in its nature, and that is operable by the movement of the locomotive for thereby relieving the engineer from the necessity of 15 operating the whistle mechanism at grade crossings, stations and the like.

The primary object of my invention is the provision of such a whistle actuating mechanism for locomotives, that is comparatively 20 simple in construction, and one that will operate effectively under all conditions.

A still further object of the invention is to provide a mechanism for locomotives 25 wherein the same may be thrown out of operation at will, and wherein means is provided for indicating to the engineer the names of the different stations that his train is approaching.

30 The nature and advantages of the invention will be better understood when the following detailed description is read in connection with the accompanying drawings, the invention residing in the construction, combination, and arrangement of parts as 35 claimed.

In the drawings forming part of this application, like numerals of reference indicate 40 similar parts in the several views, and wherein:

Figure 1 is a fragmentary rear elevation of one side of a locomotive equipped with my novel whistle mechanism.

Figure 2 is a similar view of the front 45 end of the locomotive, a portion of which is shown in cross section, for more clearly disclosing certain portions of my mechanism.

Figure 3 is a detail vertical cross section taken substantially upon the line 3—3, and 50 looking forwardly in the direction of the arrows.

Figure 4 is a fragmentary top plan of a particular form of endless chain employed in conjunction with this invention.

55 Figure 5 is a side elevation thereof, and Figure 6 is what may be termed a plan

view of an electrical actuating mechanism for the locomotive whistle.

First, having reference to Figures 1 to 5 of the drawings, 5 designates generally a locomotive equipped with a wellknown form 60 of whistle 6. In the furtherance of my invention, the front axle 7 of the front locomotive truck 8 is equipped with a worm gear 9, that is in mesh with a vertical worm gear 10, suitably journaled between bearings 11, that are carried by said axle 7. Supported above said axle 7 is a gear box 12, within which is a desirable form of reduction gear 65 (not shown), that is driven by said worm 10.

One shaft of this reduction gearing projects outwardly of the box 12 that is equipped with a spur gear 13, that is adapted for intermesh with a spur gear 14 upon a stub 75 shaft 15, that is universally connected at 16 to the lower end of a vertical shaft 17. This shaft 17 is suitably journaled within an opening in the floor 18 of the locomotive at one end, and within a bearing 19 carried 80 by a bracket 20 upon the front end of the locomotive boiler at its upper end.

Keyed to the vertical shaft 17 adjacent its upper end is a sprocket wheel, while in direct alinement with this sprocket wheel and 85 within the cap of the locomotive, is a similar sprocket wheel 21, that is journaled within a bracket 22. Trained over these alined sprockets is an endless chain 22', that is preferably of the form shown in Figures 90 4 and 5.

As clearly shown in these figures, as well as in Figure 3, opposite sides of desirable ones of the links are equipped with upstandings plates 23, each of which is formed at 95 its upper edge with a suitable number of notches 24, the number of these notches corresponding to the number of times in quick succession, it is desired that the whistle 6 be blown. As shown in Figure 5, certain 100 sides of these notches are bevelled for purposes presently to be set forth, and that the notches of the plates on one side of the plates are bevelled upon edges opposite from the edges of the notches upon the plates on the 105 other side of the chain links.

Immediately above this chain 22, and at the inner side thereof is a freely vertically movable bar 25, that is held within guide brackets 26 secured to the boiler of the locomotive. Upon the lower end of this rod 25, there is pivotally secured at 27 a yoke 28

that comprises a pair of legs as shown in Figure 3. The portion of this yoke above its pivotal connection to the rod 25 is formed with an arcuate slot, through which extends 5 a set screw 29, that engages at its screw threaded end within a screw threaded opening of the said rod, whereby this yoke may have either one of its legs in position to engage the upstanding plates 23 upon opposite 10 sides of the links constituting said chain 22. Directly above this rod 25 and pivoted to the uppermost rod bracket 26 is a bell crank 30, the lower arm of which has contact with the upper end of said rod, while the upper 15 arm is in engagement with the lower end of the usual actuating lever 6' of the whistle 6. The lower ends of the legs constituting said yoke are bevelled, it being at once apparent that as the chain 22 is moved by the action 20 of the locomotive, and that when the yoke is set as in Figure 3, the proper ones of the plates 23 carried by the chain will engage beneath the adjacent leg of the yoke for thereby moving the rod 25 upwardly and 25 consequently blowing the whistle. The distance between the notches 24 in the plates 23 control the length of time that the whistle will be blown, and the number of notches in these plates, regulate the number of times 30 that the whistle will be blown, it being of course understood that plates formed with varying number of notches, and these at different spaces apart, will control the blowing of the whistle at grade crossings, curves, 35 and the like, that is now required by law.

Upon a return trip of the locomotive bearing this whistle actuating mechanism, it will be necessary that the yoke be moved over into a different position, for consequently 40 engaging the opposite leg thereof with the plates upon opposite sides of the links constituting the chain 22.

As a means for setting said chain 22, the sprocket gear 21 may be rotated by the engineer through the medium of a crank 45 handle 31.

Extending through an opening in the floor board 18 of the locomotive at its front end, and pivotally secured at 32 beneath said opening is a rocking lever 33, the lower end of which is operatively connected to the stub shaft 15, the upper end of said rocking lever being pivotally connected to one end of a rearwardly directed rod 34. The opposite 55 end of this rod has pivotal connection to one end of a hand lever 35 within the locomotive cab, which hand lever carries a suitable detent 36, for cooperation with a notched segment 37, it being of course apparent that 60 a movement of this hand lever 35 will cause a swinging movement of the stub shaft 15 for engaging or disengaging the gear 14 from the gear 13, for thereby connecting or disconnecting the whistle actuating mechanism 65 from the locomotive.

Certain of the links constituting the chain 22 are formed centrally with upstanding fingers 38, that are adapted to engage teeth 39 upon a drum 40, that is suitably journaled within the locomotive cab. This drum 40 70 carries the names of the different stations in the line of travel of the locomotive, whereby a movement of the chain will consequently rotate this drum for bringing to view through an opening in a cover plate 42, the 75 name of the town or city being approached.

In Figure 6, there is shown an electric means for actuating the whistle 6, and in this instance, an upstanding plate 23' of the chain 22' will engage a finger 43 upon one 80 end of a pivot contact arm of an electric switch. Above this arm, is a stationary contact 44. When the pivotal contact 43 is raised by the said plates 23', the circuit will be completed through a battery 45 to an electromagnet 46, which will attract an armature 47 upon one arm of a bell crank 48 that is pivoted to a suitable bracket 50 upon the locomotive boiler. The opposite arm of said bell crank is in close contact with the said lever 6' of the whistle 6 for thereby operating said whistle at each energization of the magnet. 85

In view of the above description, it is believed by me that the operation and advantages of a whistle actuating mechanism for locomotives of the present character will be readily appreciated by those skilled in the art, and although I have herein shown and described the most preferred embodiments of the invention with which I am at present familiar, it is nevertheless to be understood that minor changes may be made therein, without departing from the spirit and scope of the invention as claimed. 95

Having thus described my invention, what I claim as new, and desire to secure by Letters-Patent, is:

1. In combination with a locomotive, means operatively connected to the running gear of the locomotive for automatically actuating the whistle thereof, and means for disconnecting said first mentioned means. 100

2. In combination with a locomotive wherein the same includes the usual signalling whistle, an endless chain operatively connected to the running gear of the locomotive, abutments upon the chain, and means operatively connected to said locomotive whistle to be engaged by said abutments during the movement of the chain for blowing said signalling whistle. 115

3. In combination with a locomotive wherein the same includes the usual signalling whistle, an endless chain operatively connected to the running gear of the locomotive, abutments upon the chain, and means operatively connected to said locomotive whistle to be engaged by said abutments 120 during the movement of the chain for blow- 125

ing said signalling whistle, and manual controlled means for disconnecting said chain from the locomotive running gear.

4. In combination with a locomotive wherein the same includes the usual signalling whistle, an endless chain operatively connected to the running gear of the locomotive, abutments upon the chains, and

means operatively connected to said locomotive whistle to be engaged by said abutments during the movement of the same for blowing said signalling whistles, and means whereby said chains may be manually controlled for setting said chains.

In testimony whereof I affix my signature.
ELDON R. WATKINS.
